UNITED STATES PATENT OFFICE.

SAMUEL C. PANDOLFO, OF ST. CLOUD, MINNESOTA.

TABLE.

1,412,314.

Specification of Letters Patent. Patented Apr. 11, 1922.

Application filed May 20, 1920. Serial No. 382,714.

To all whom it may concern:

Be it known that I, SAMUEL C. PANDOLFO, a citizen of the United States, and a resident of St. Cloud, in the county of Stearns and

5 State of Minnesota, have invented a certain new and useful Improvement in Tables, of which the following is a description, reference being had to the accompanying drawings, which form a part of my specification.

10 My invention relates to a table entirely constructed of metal and so formed as to permit collapsing or folding into compact form when not in use; while at the same time providing a construction which may be 15 easily "set up" and possess the desired rigidity or stability, with the movable parts thereof firmly held in their extended or "set up" position when the table is in use.

The object of the invention is to provide 20 a non-warping and indestructible table adapted to various uses and which may be collapsed into such compact form that it can be readily stored or placed in a comparatively shallow or small space for transportation or storage.

The objects and advantages of my invention will be readily comprehended from the following detailed description of the drawings, wherein:

30 Figure 1 is a perspective view of my improved table in "set up" condition.

Figure 2 is a vertical sectional view thereof, taken at any point between the leg-sides.

Figure 3 is a similar sectional view but 35 showing the parts in folded or collapsed condition.

Figure 4 is a cross sectional view taken on the line 4-4 of Figure 3 looking in the direction of the arrows.

40 Figure 5 is a detail sectional view taken on the line 5-5 of Figure 2 looking in the direction of the arrows.

The specific embodiment of my invention as illustrated in the drawings comprises a 45 top 10 composed of sheet metal of any desired size or dimensions, with the marginal edges preferably turned down at right angles or flanged as shown at 11 so as to reinforce the top and prevent possibility of bending. The turned down end or flange at one side of the table top is provided with cut-out portions as at 12, 12 see Figure 1; the cut-out portions being of width commensurate with the width of two legs or supporting members when the latter are arranged in folded, parallel relation with each

other, in order that the top may fold into substantially parallel relation with the folded legs, as shown in Figure 3.

The supporting members or legs are operatively arranged in pairs; the one pair comprising the legs 13, 13, which are pivotally mounted at 14 to the flanges or turned down edges 11 of the table-top at opposite sides thereof, but at the same end of the table-top and preferably with the ends of the legs arranged on the inside of the flanges 11. The pivotal relation between the legs and the top is such that the latter may swing either into the horizontally disposed position shown in Figures 1 and 2 or be swung into the depending or folded position shown in Figure 3. The other set or pair of supporting members comprises the legs 15, 15, connected together at their upper ends by 50 a suitable rod or member 16 which may be riveted or otherwise secured to the upper ends of both legs 15, as no rotative movement between the rod 16 and the upper ends of the legs 15 is contemplated or necessary. 55 The legs 15 are arranged between the legs 13, 13, that is intermediate of the vertical plane of both legs 13, in order that the upper ends of legs 15 may be disposed between the flanges 11 at opposite sides of the table-top 10. The legs 15 at a suitable point intermediate of their ends are pivotally mounted on the cross-member or rod 17, which extends through the legs 15 and either rotatably secured in or riveted to the legs 13, 60 13 so as to maintain the X-shaped or "saw-buck" relation between the two pair of legs. The connecting member or rod 17 is preferably slightly reduced where it passes through the legs 13 and 15, as shown at 18, 65 90 in order to provide a shoulder at the inner sides of the legs 15, 15 so as to also act as a spacing member to maintain the legs 15, 15, in proper spaced relation and therefore 95 against sidewise movement.

At a suitable point adjacent the lower or free ends of legs 13, 13, I prefer to provide the tie-rod or brace member 19 riveted or otherwise properly secured at its ends to both legs to reenforce the lower ends thereof and prevent possibility of spreading or bending; while the legs 15, 15 are likewise provided with a cross-member or tie-rod 20 riveted or otherwise secured to both legs 15, 15 but at a point or elevation disposed in a different horizontal plane from that of the tie-rod or brace member 19, in order 100 105 110

that the tie-rods 19 and 20 will not interfere with a proper collapsing or folding of the table.

For the sake of lightness and in order that the legs may have sufficient strength I prefer to construct them of long sheet metal strips of desired length; each strip being folded lengthwise upon itself into U-shape in cross-section, as more clearly disclosed in Figure 4. The upper ends are preferably slightly extended beyond the rounded or curved portion and reduced and rounded, as shown at 21, see Figure 3; and these ends are preferably forced together; the ends being preferably extended beyond the rounded edge or bend of the strip as previously described, so as to prevent any undesirable buckling of the metal. By bringing the upper ends into the compact or intimate relation as shown at 22 in Figure 5, a better riveted or firmer relation may be provided between the pivots 14 in the one instance or the rod 16 in the other instance. The rod 16, as well as rods 19 and 20, are also preferably provided with slightly reduced ends, similar to the ends of rod 17, where they pass through the respective legs; and these reduced ends may be slightly slit to enable the ends to be readily swaged to provide the desired binding relation with the legs.

In order to further reenforce the lower ends of the channeled legs and at the same time provide a smooth non-cutting surface at the bottom of each leg, they are each cut at a suitable angle as shown at 23, so that when the leg is in "set up" position the entire bottom edge of each leg will be disposed parallel with and in supporting relation with the floor. Furthermore, I prefer that one side or portion of each channel or leg at its lower end, during the process of manufacture, be extended beyond the remaining portion thereof so as to provide a lip which is then bent back so as to come intermediate of the sides of the channel or sides of the leg and thereby provide a closed lower end to the channel; the lip or projection being welded or otherwise integrally secured to the respective sides of the channel to provide a smooth closed bottom which will in no way mar the floor and which at the same time will prevent the legs cutting into or embedding themselves in the ground when the table is used in the open.

In order to prevent a binding relation between the various legs and at the points where they are pivoted to the table-top, I prefer to employ spacing members or washers as shown at 24, see Figure 4. The spacing members 24 will permit the legs to be more easily manipulated, while at the same time they will prevent a rubbing contact between the legs which might mar or injure the finish thereon.

A portion of one of the flanges or turned

edges 11 of the top 10, namely the flange at the side of the top toward which the upper ends of the legs 15, 15 move when brought to "set up" position, is provided with an extension or lip 25, see Figures 2, 3 and 5, 70 which is bent back beneath the top 10 and preferably slightly curved intermediate of its ends, toward the top so as to somewhat restrict the space therebetween. As is apparent from the construction shown, this lip 75 will be disposed along the path of the connecting rod 16, which secures the upper ends of the legs 15, 15 together, and the curved portion of the lip will permit the rod 16 to be forced past said curved portion toward 80 the flange 11 and firmly hold the rod 16 in place against the flange 11 and therefore lock the legs 15, 15 against accidental collapsing. It is understood, of course, that the lip or clip 25 is sufficiently resilient to 85 enable the rod 16 to be forced past the clip and that the latter will spring back into normal position.

In order to permit the two sets or pairs of legs 13 and 15 to fold into substantially parallel relation when the table is collapsed, I prefer to provide the one pair of legs, to-wit each leg 15, with a notch, as at 26, disposed transversely of each leg 15, at a point coincident with the rod 19, of the other pair of legs, when the legs are folded into parallel relation, as shown in Figure 3.

In order that the top 10, when the table is collapsed, may extend parallel with the folded legs, I prefer to provide the flanges 11, at opposite sides of the table and at a predetermined point adjacent the end of the top which is supported by the movable legs 15, with a slight notch or cut-away portion, as at 27, see Figures 1 and 2, for the purpose 100 of receiving the outer riveted ends of the rods 17, as shown in dotted lines in Figure 3. In constructing the table, for the sake of appearance, I prefer to have the rounded edge of the legs disposed upwardly, as shown in 105 the drawings; and it is apparent that metallic rods may be employed for forming the legs instead of the channel strips shown in the drawings; I however, prefer to employ the latter construction on account of lightness, while at the same time possessing the requisite strength. It is also evident that the table may be of any dimensions in height and the table-top given any desired shape and also provided with any desired design, 110 as for example illustrated in Figure 1.

I have shown and described what I believe to be the simplest and best embodiment of my invention; but modifications may be made in certain details of construction without departing from the spirit of my invention.

What I claim and wish to secure by Letters Patent is:

1. A table of the character described, 130

comprising a sheet metal top, the edges whereof are bent downwardly, with the edge at one side of the top being provided with an integral lip disposed beneath the 5 top, a plurality of legs composed of sheet metal bent longitudinally into U-shape in cross-section and arranged in pairs, the intermediate portion of the metal between the sides being extended at the bottom of 10 the legs and bent back between the side portions to provide flat closed lower ends for the legs, the legs of one pair being pivotally secured at their upper ends on the inside of the turned edges of opposite sides at one 15 end of the top, a brace-rod secured to the legs of said pair at a point intermediate of their ends and shouldered adjacent to said legs, the legs of the other pair being pivotally mounted intermediate of their ends 20 on said brace-rod between the shoulders thereof and the legs of the first mentioned pair, and a brace-rod disposed between the upper ends of the legs of said second mentioned pair, said brace-rod being adapted 25 to pass between said lip and the top, whereby the second pair of legs are locked in "setup" position, the turned down edge provided with the integral lip being cut away at opposite ends to permit the top and 30 both pairs of legs to fold into substantially parallel relation.

2. A table of the class described, comprising a sheet metal top, the edges whereof are turned downwardly, with the edge at 35 one side of the top being provided with an integral lip or extension bent back beneath the top, a plurality of legs composed of sheet metal bent into channel form, with a portion at the lower end of each sheet provided with a lip or extension bent back between the sides of the channel so as to provide a smooth closed end at the lower ends 40 of the legs, the legs of one pair being pivotally secured at their upper ends to the 45 turned down edges of opposite sides at one

end of the top, a tie-rod disposed between the legs of said pair and connected thereto at an intermediate point, the legs of the second pair being pivotally mounted at a point intermediate of their ends on said tie-rod, 50 the upper ends of the legs of said second pair being secured together by a tie-rod, said tie-rod being adapted to be engaged by said lip integral with the edge of the top to lock the second pair of legs in "set 55 up" position, the turned down edge of the top provided with said lip being cut away at opposite ends thereof to permit the top and both pairs of legs to fold into parallel relation with one another when the table 60 is in "knocked down" condition.

3. A table of the class described, comprising a sheet metal top, the marginal edges whereof are turned downwardly, metallic legs arranged in pairs and adapted 65 to extend diagonally in opposite directions, the legs of one pair being pivotally mounted at their upper ends to the turned down edges at one end of the top, a cross-rod disposed between the legs of said first pair 70 and secured thereto at points intermediate of their ends, said cross-rod being shouldered adjacent the ends and intermediate of the legs of the first pair, the legs of the second pair being pivotally mounted at a 75 point intermediate of their ends on said cross-rod and intermediate of the shoulders and the legs of the first pair, the upper ends of the legs of the second pair being adapted to abut against the turned down edge at one 80 end of the top, the turned down edge with which the second pair of legs contacts being notched or cut away to permit the top and both pairs of legs to fold into parallel relation with one another when the table is 85 in "knocked down" condition.
